Patented July 22, 1919.

UNITED STATES PATENT OFFICE.

EDWARD J. LEMAN, OF MORTON, ILLINOIS.

LIFTING-JACK.

1,310,498.

Specification of Letters Patent. Patented July 22, 1919.

Application filed May 1, 1917. Serial No. 165,694.

To all whom it may concern:

Be it known that I, EDWARD J. LEMAN, citizen of the United States, residing at Morton, in the county of Tazewell and State of Illinois, have invented certain new and useful Improvements in Lifting-Jacks, and do hereby declare that the following is a full, clear, and exact description of the invention, which will enable others skilled in the art to 10 which it appertains to make and use the same.

This invention relates to a lifting jack and more particularly to a lifting jack for automobiles.

15 One of the objects of the invention is to provide a jack for engaging the wheel of an automobile or other vehicle that can be clamped thereto making a rigid support for the same.

20 Another object is to furnish a jack for each wheel which in the act of lifting the wheel will automatically clamp itself thereto and act to support the vehicle which can be shifted from place to place on the floor 25 or turned around as upon a turn-table, the jack being provided with supporting wheels for the purpose.

Another object is to furnish a jack having 30 a part to engage beneath the hub of the wheel of the vehicle and having a part to engage over the rim or felly of the wheel, the relation of the parts being such that when the wheel is raised it will be firmly clamped so that the wheel and jack are as 35 though a single structure.

Another object is to provide a jack that can be clamped firmly and rigidly to the wheel of a vehicle and provided with caster-wheels which in use will lie outside of the 40 point of contact of the wheel with the ground surface.

To the end that the invention may be understood I have provided the accompanying drawing, in which,

45 Figure 1 is an end elevation of the jack showing its position adjacent the wheel ready for lifting the same.

Fig. 2 is a similar view showing the wheel raised and supported on said jack.

50 Fig. 3 is a rear elevation of the jack.

Fig. 4 is a plan of the jack on a much smaller scale showing certain parts in section; and,

55 Fig. 5 is a cross section of the frame on line $x-x$, Fig. 4.

The jack consists first of a supporting

frame or platform which may be constructed in one of several ways. It may be cast or, if preferred, may consist of a single length of metal bar of the desired cross sectional area formed into an elongated frame A whose terminal ends may abut as shown in Fig. 4, the two sides of the frame being substantially parallel. Said frame incloses at each extremity a suitable casting B secured in said frame by means of bolts C, for example, said castings having beneath each of them a caster-wheel D swiveled thereto and adapted to freely swing about their pivots E in said casting B. These casters may 60 be of any approved form and preferably of the ball-bearing variety.

F is a brace substantially in the form of a V, its ends being suitably secured to one of the parts of the frame by means of rivets 65 G, for example, the base of the brace being preferably flattened so as to receive the terminal ends of the frame A and each of the latter is secured thereto by means of rivets H, for example, said rivets also passing 70 through the base of a portion of a U-shaped yoke J securing all in a thoroughly rigid manner.

The said yoke is provided with one or 75 more holes K, Fig. 5, one of them receiving a bolt L acting as a pivot for a member which terminates at its outer end in a hook M adapted to overlie the rim or felly of the wheel as shown in Fig. 2, whose purpose 80 will be explained presently.

N N indicate two spaced uprights lying 85 substantially parallel to one another and preferably made of channel-bar, their lower ends being secured to the frame A by means of bolts or rivets O, Fig. 4. These are held 90 rigidly in a perpendicular position by means of diagonal braces P whose upper ends are suitably secured to them, the lower ends of the braces being secured to the opposite side of the frame by means of bolts or 95 rivets Q.

Between the upper ends of the uprights N is pivoted at R R a lever S in the form of a yoke, by preference, the free ends of which extend beyond the pivots, and T is a stirrup 100 whose extremities are pivoted relatively to the extended ends of the described portion S, for instance on a bar or rod U. The manner of using the jack is clearly shown in the first two figures wherein after placing it close to 105 the wheel indicated by 2 with the hook M overlying the felly the lever S is made to 110

occupy a position which will permit the stirrup T to be engaged beneath the hub V of the said wheel.

By depressing the lever the wheel is raised 5 thereby bringing its felly up into the hook M, the continued lifting movement drawing the felly firmly into the hook. In the continued lifting action the tendency is to shorten the distance between that part of 10 the felly upon which the hook rests and the pivot L of the latter. This draws the wheel and the frame A of the jack firmly together, acting to clamp them one to the other. In addition the wheel is clamped between the 15 hook M and said stirrup and as the full downward movement of the lever is completed it is moved inward until the pivot points of the parts, S, T, are in such a relation that the weight of the vehicle cannot 20 re-act to raise said lever, the latter being preferably placed against the spokes of the wheel, thus carrying the pivot at U outward or outside of a vertical line drawn through the centers of the said pivot U and the pivot 25 R. The stirrup may be provided with one or more holes W for adjusting it relatively to the lever S to accommodate wheels of different diameters. Also, the holes K in the U-shaped member J admit of the adjustment 30 of the hook M for the same purpose.

Slight changes may be made in the structures without departing from the inventive idea, it being observed that the introduction of the hook M operating as a clamping member in conjunction with the stirrup T results in firmly clamping the wheel and the jack together so that by attaching one of the jacks to each wheel the vehicle is then supported above the floor so that it may be 40 shifted to any position desired or be readily turned around.

The simplicity of the jack and the fact that it can be thus clamped to a wheel makes it of the greatest value for the quick lifting 45 of the tires from the floor for removing the weight from them when the vehicle is not in use.

If used for this purpose only the casters D need not be used but their addition admits 50 of the ready shifting of the vehicle from place to place on occasion.

Having thus described my invention, I claim:

1. A jack for engaging in the wheel of an 55 automobile comprising a wheeled platform, a hook pivoted at one end thereon and adapted at its hooked end to pass through the wheel and engage over its rim for holding the same against the said platform, a 60 standard supported upon the platform, and a lifting part thereon to engage and lift the wheel, the relation of the lifting part both

to the portion of the wheel which it engages and to the said hook being such that the higher the wheel is lifted toward its limit 65 of raising movement the more firmly it is forced up into the hook and the more firmly the rim is held against said platform by said hook.

2. A jack for engaging the wheel of and 70 transporting automobiles comprising a wheeled platform, a hook pivoted at one end thereon and adapted at its hooked end to pass through the wheel and engage over its rim for holding the same against the said 75 platform, a standard supported upon the edge of the platform lying nearest the wheel-rim, and a lifting part thereon to engage and lift the wheel, the relation of the lifting part both to the portion of the wheel 80 which it engages and to the said hook being such that the higher the wheel is lifted toward its limit of raising movement the more firmly it is forced up into the hook and the more firmly the rim is held against said 85 platform by said hook.

3. A jack for engaging and lifting a wheel of a vehicle comprising a platform, a member pivoted upon and extending laterally from the platform terminating in a downwardly turned hook outside said platform in position to engage over the rim of the wheel at the side thereof remote from the platform, a standard uprising from the platform, and a part mounted thereon to engage 90 the wheel-hub for lifting the wheel-rim into the hook and for sustaining the wheel in the raised position, said hook adapted in the lifting movement to draw the rim toward and clamp it against the platform. 95

4. A jack including in its construction a platform including spaced portions forming an open frame, a wheeled member for each end of said platform having a part adapted to enter between the portions and also having an extended shoulder to receive the portions upon it, means to secure the said part to the portions, a yoke secured inside the platform to one of the portions including a series of holes, a member lying at one end 100 within the yoke and having a downwardly turned hook at its other end lying outside the platform, means to pivotally support the member at any one of the holes, a standard erected upon the platform at that side thereof beyond which the hook extends, and a lifting and supporting member carried by the standard. 110

In testimony whereof I affix my signature, in presence of two witnesses.

EDWARD J. LEMAN.
